ORIN BENNETT, OF PLACERVILLE, CALIFORNIA.

CARRIAGE-RETURN MECHANISM FOR TYPE-WRITING MACHINES.

1,151,756.

Specification of Letters Patent. Patented Aug. 31, 1915.

Application filed August 21, 1914. Serial No. 857,842.

To all whom it may concern:

Be it known that I, ORIN BENNETT, a citizen of the United States, residing at Placerville, in the county of Eldorado, State of California, have invented certain new and useful Improvements in Carriage-Return Mechanism for Type-Writing Machines; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in typewriting machines and particularly to a mechanism for returning the carriage to normal starting position by an electrical control apparatus and simultaneously therewith turning the platen such a distance as may be required. This electrical return mechanism is designed to obviate the necessity of returning the carriage to the starting point by hand and also the necessity of turning the platen by hand or by the hand operated mechanism now commonly used.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a rear elevation of the framework of a typewriting machine showing the carriage thereon and my improved return mechanism. Fig. 2 is a fragmentary portion showing the carriage in the position of its limit of travel. Fig. 3 is an end view of the subject matter shown in Fig. 2. Fig. 4 is a front view of a core centering structure.

Referring now more particularly to the characters of reference on the drawings the numeral 1 designates the frame of a typewriting machine, the numeral 2 the carriage which slides thereon, and the numeral 3 the platen carried by the carriage.

My invention divides itself into two subdivisions, namely, the platen return mechanism and the carriage rotating mechanism

and describing first the platen rotating mechanism it is pointed out that the numeral 4 designates an annular ratchet rack fastened on the end of the platen 3. Engageable with this rack 4 is a spring pressed dog 5 turnably mounted on a pin 6 journaled in a small supporting frame 7 on the carriage 2. This pin 6 has secured thereto an upper projecting cam finger 8 and a lower projecting curved cam finger 9. As the carriage 2 moves from its starting point to its limit of movement the finger 8 engages a cam 10 secured stationary to the frame 1 which engagement causes the shaft 6 to rotate to move the spring pressed dog 5 to its limit of movement and likewise moves the member 9 to its lower limit of movement. Then when the carriage 2 is returned to its normal starting position in the manner as will be hereinafter described the curved cam finger 9 engages a cam likewise secured stationary to the frame 1 which action moves such cam finger 9 upwardly and through the medium of the pin 6 moves the spring pressed dog 5 downwardly to its limit of movement. Thus since the upper side of the dog 5 is curved and its lower edge is square, when it moves upwardly it will move past the ratches 4, but when it moves downwardly will engage one of said ratches and move the platen 3, the amount of such movement being of course adjusted by the amount of movement allowed the fingers 8 and 9. Thus it will be seen that each time the carriage moves forward and is returned to the starting point the platen 3 will be automatically turned thus obviating the necessity of turning it by hand or by a hand controlled mechanism. I provide a band spring 9a to engage the finger member 9 as it moves downwardly so that it will not move beyond its normal operative position.

Describing now the carriage return mechanism I provide an arm 12 secured to the front end of the carriage 2 and provided with an eye 13 at its lower end. Projecting through the eye 13 is a core 14 having two pins 15 and 16, one on each side of the eye 13, whereby with the movement of the core 14 the arm 12 and incidentally the carriage 2 will be moved. The core 14 moves in the solenoid coil 17 whenever the same is supplied with electric current and this electric current is supplied by means of the following structure namely: A wire 18 leads from any suitable source of supply to the coil 17.

Another wire 19 leads from the opposite terminal of the coil 17 to a hinged spring pressed switch blade 20 having a contact point 21. Hinged adjacent the switch blade 20 is another switch blade 22 having a contact point 23 engageable with the point 21 under certain conditions and normally held out of engagement with the same by means of a spring 24. A wire 25 leads from the switch blade 23 to the source of current supply.

When it is desired to return the carriage 2 to the starting point a key 26 which is located at the front of the machine is pressed 15 and with the pressure on this key a shaft 27 to which it is connected is turned. This shaft 27 extends from the front to the rear of the machine and is provided with an upwardly projecting arm 28 on its rear end 20 which has a bent portion 29 engaging the switch blade 22 so that with the operation of the key 26 the blade 22 will be moved on its pivotal point bringing the points 23 and 21 together and connecting the electric 25 circuit from the source of supply 30 through the wire 18 to the coil 17 through said coil and through the wire 19 to the point 21, through the points 21 and 23 and wire 25 back to the source of supply. This will 30 cause the coil 17 to act on its core 14 to draw it from the center of the coil, which action will pull on the eye 13 and arm 12 and return the carriage to normal starting position. When pressure is taken off of the key 26 35 the spring 24 will disengage the points 21 and 23; but to make this action absolutely positive I have provided a projecting finger member 31 on the arm 12 which with the backward movement of the carriage 2 engages the switch blade 20 and moves it away 40 from the switch blade 22 so as to break the connection between the points 21 and 23 in a positive manner each time.

The sudden shock due to the action of the coil 17 would ordinarily throw the carriage back with a tremendous jerk but this will be overcome by the spring tension in the forward escapement of the carriage which would be of any desired type, but preferably of that 50 type shown in my pending application for patent, Ser. Number 857,841 filed August 21st, 1914. With the action of this spring the sudden jerk or jar would be compensated for so as to return the carriage with 55 ease of movement although very rapidly.

The purpose of the pins 15 and 16 engaging the eye 13 instead of having a fixed connection is to allow the positive centering of

the core 14 in the coil 17 as is necessary to efficient action and which is permitted of by 60 the loose connection thus noted.

From the foregoing description it will be readily seen that I have produced a rapid and effective electrically controlled mechanism which is extremely advantageous for 65 the purposes noted.

From the foregoing description it will also be readily seen that I have produced such a device as substantially fulfills the object of the invention as set forth herein. 70

While this specification sets forth in detail the present and preferred construction of the device, still in practice such deviations from such detail may be resorted to as do not form a departure from the spirit of 75 the invention.

Having thus described my invention what I claim as new and useful and desire to secure by Letters Patent is:

1. A device of the character described 80 comprising the combination with a slidable carriage and a turnable platen mounted on said carriage, of an annular rack mounted on said platen, a spring pressed dog engaging said rack, a turnable pin secured to said dog and suitably journaled, a pair of spaced cam fingers on said pin and cams engageable with said fingers to move one in one direction when the carriage moves in one direction and to move the other in the opposite 85 direction when the carriage moves in another direction, as described.

2. A device of the character described comprising the combination with a slidable carriage, of an arm secured to said carriage, 95 a solenoid coil, the core of said coil being connected with said arm, a source of electrical energy, wired connections from said source of electrical energy to said solenoid, a switch interposed in said wired connections for making and breaking the electrical circuit from said source of electrical energy to said solenoid, said switch comprising two pivoted members having contact points adapted to be brought into contact with each 100 other, and a finger member on said arm engageable with one of said pivoted members with one movement of said carriage, as described.

In testimony whereof I affix my signature 110 in presence of two witnesses.

ORIN BENNETT.
